Gustav Schulze,
By his Atty., O. B. Reichelt.

UNITED STATES PATENT OFFICE.

GUSTAV SCHULZE, OF EISLEBEN, GERMANY.

CEMENT ROOFING-TILE.

SPECIFICATION forming part of Letters Patent No. 605,654, dated June 14, 1898.

Application filed January 9, 1896. Serial No. 574,838. (No model.) Patented in Germany October 24, 1894, No. 83,860; in Hungary November 11, 1894, No. 1,576; in Belgium November 15, 1894, No. 102,453; in Switzerland November 29, 1894, Nos. 9,499 and 9,500; in Austria December 1, 1894, No. 44/6,198; in Italy December 21, 1894, No. 37,684, and in France February 8, 1895, No. 242,534.

To all whom it may concern:

Be it known that I, GUSTAV SCHULZE, manufacturer of tile-machines, a citizen of the Kingdom of Prussia, residing at Eisleben, in the Kingdom of Prussia, German Empire, have invented certain new and useful Improvements in Cement Roofing-Tiles, (for which patents have been obtained in the following-named countries: Austria, December 1, 1894, No. 44/6,198; Hungary, November 11, 1894, No. 1,576; France, February 8, 1895, No. 242,534; Italy, December 21, 1894, No. 37,684; Switzerland, November 29, 1894, Nos. 9,499 and 9,500; Belgium, November 15, 1894, No. 102,453, and Germany, October 24, 1894, No. 83,860;) and I do hereby declare the following to be a full, clear, and exact description of the invention, such as will enable others skilled in the art to which it appertains to make and use the same.

This invention relates to improvements in roofing-tiles, and has for its object to provide a tile formed of cement which shall be light, strong, and impervious to moisture.

The invention consists in the parts shown in the drawings, described in the specification, and pointed out in the claims.

In the drawings, Figure 1 is a plan view of the outer side or face of one of my improved tiles; Fig. 2, a vertical section thereof in line A B of Fig. 1; Fig. 3, an edge view looking from the right side of Fig. 1; Fig. 4, a plan view of the under side of said tile; Fig. 5, a horizontal section in line C D of Fig. 1; Fig. 6, a section in line E F of Fig. 1; Fig. 7, a plan of a series or number of rows of tiles made to conform to my invention and fitted to interlock with each other; Fig. 8, a vertical section in line I K of Fig. 7; Fig. 9, a section of a series of interlocked tiles in line L M of Fig. 7; Fig. 10, a horizontal section in line G H of Fig. 7.

The tiles hereinafter described are made of cement, sand, and water properly mixed to form a mortar which will dry in the open air without the use of artificial heat or a drying-room, but need only to be placed under an open shed to be protected from the weather. Roofing-tiles formed of this material have

proved of superior quality and are light, 50 strong, and impervious to moisture and are of small cost compared with tiles or roof-covering made of other material having like durability. Tiles made of this material must be so formed that they will fit snugly and securely together, and by my improved form and construction of tile this is fully accomplished without the employment of nails, wire, or other separate fastening devices, and a tile is produced which will fully answer all required purposes.

My improved tile, as clearly shown upon the outside section, edge, and under side in the first four figures of the drawings, is molded to the form of a square plate 1, a number of 55 which are placed in diagonal tiers or rows, as shown in Fig. 7, with the two lower lap edges 2 of each tile having a downwardly-projecting bead 10, which rests above and upon the two upper lap edges 3 of the other or adjacent 60 tiles next below it. In order to secure this lap-joint, the opposite horizontal corners of each tile are cut off in parallel lines 4 of the diagonal length of the lap edges 2, and thus allow the tiles to abut solidly at their adjacent corners one against the other.

The two upper lap edges 3 have a channel 5, running parallel to the adjacent sides of the tile from the lower ends of the corner-lines 4 of the tile until they meet at right angles at the upper corner of the tile, and the said channels 5 are bounded on the outside by a raised bead 6, which merges into an outer groove 7 at the very edge of the tile. The groove 7 is used as a mortar-groove and extends from a short distance above the upper ends of the corner-lines 4 to the apex of the tile and is easily reached from the inside to be filled or pointed up either when the tiles are laid or afterward should the joint require 85 attention.

Upon the under edge of the tile, as shown in Fig. 4, a pocket or recess 8 is formed beneath the extended portion of the bead 6 and between the lower end of the mortar-groove 95 7 and the horizontal corner of the tile to receive each one of the sides and ends of a retaining-nose 9, formed to project downwardly

from the under side of the tile, as will hereinafter appear.

A bead 10 is formed on the under side of the tiles to extend from the horizontal corners 5 parallel with the two lower sides until they meet above the lower corner or point of the tile, the said bead 10 being so located that it will snugly fit into the channels 5 upon the upper face and lap edges 3 of the tile and 10 serve as the principal means for interlocking the tiles together.

A mortar-groove 11 is formed at the edges of the parallel corner-line 4, which abut against each other at the said horizontal corners and 15 provide a useful and conveniently-located means for holding the four meeting corners of the tiles together.

The tiles rest upon purlins or small strips of wood secured to the rafters of the roof and 20 are each interlocked with one of said purlins by a hang-nose 12 at the under side of the apex or upper corner thereof, which extends below the said purlin, as clearly shown in Fig. 8 of the drawings, and together with the 25 retaining-nose 9 at the lower part of the tile will securely hold the tile upon the roof, when they are made to interlock with each other, as above described.

A hub 13, with star-points extending therefrom upon the under side of the tiles, comes 30 directly over the purlins and may be supported thereby and raised to insure tightly-fitting contact with the roof and with each

other besides serving to greatly reinforce the tiles.

I claim as my invention and desire to secure by Letters Patent—

1. A tile made in the form of a square plate having its side corners cut away, two upper lap edges having an inner channel and a raised 40 head, and two lower lap edges, each having a head to fit the said channels of the upper lap edges, a retaining-nose extending downwardly from the under side and lower corner of the tile and recesses adjoining the upper ends of the said corners to receive said retaining-nose, substantially as described.

2. A tile made in the form of a square plate having its side corners cut away and mortar-grooves formed in the edge thereof; two upper lap edges having an inner channel, a raised bead and an outer mortar-groove, and two lower lap edges, each having a bead to fit the said channels of the upper lap edges, a retaining-nose extending downwardly from the under side and lower corner of the tile and recesses adjoining the upper ends of the side corners to receive said retaining-nose, substantially as described.

In testimony whereof I affix my signature 60 in presence of two witnesses.

GUSTAV SCHULZE.
